(57) CLAIM

The ornamental design for a foot mounted cleaning device, as shown and described.

DESCRIPTION

FIG. 1 is a perspective view of the foot mounted cleaning device;

FIG. 2 is a top view of the foot mounted cleaning device;

FIG. 3 is a bottom view of the foot mounted cleaning device;

FIG. 4 is a side view of the foot mounted cleaning device;

FIG. 5 is a front view of the foot mounted cleaning device; and,

FIG. 6 is a back view of the foot mounted cleaning device.

The nature and intended use of the article in which the design is embodied is a foot mounted cleaning device to simply, quickly and effectively clean, scrub, wipe, dust or dry any floor, patio, concrete, deck, shower, tub or other similar surface.
